FINGER RING

John L. Hazelquist, Garden City, Mich., assignor to Traub Manufacturing Company, Detroit, Mich., a corporation of Michigan

Filed Feb. 23, 1966, Ser. No. 1,150

Term of patent 14 years

(Cl. D45—10)

I claim:

The ornamental design for a finger ring, substantially as shown.
